UNITED STATES PATENT OFFICE.

FRANCIS M. BARTON, OF CHICAGO, ILLINOIS.

CONCRETE BUILDING.

1,335,780.

Specification of Letters Patent.

Patented Apr. 6, 1920.

Application filed July 18, 1911. Serial No. 639,189.

To all whom it may concern:

Be it known that I, FRANCIS M. BARTON, a citizen of the United States, a resident of Chicago, in the county of Cook and State 5 of Illinois, have invented certain new and useful Improvements in Concrete Buildings, of which the following is a full, clear, and exact description.

The invention relates more particularly 10 to improvements in flat slab concrete floor, roof constructions and the like.

One object of the invention is to provide 15 an improved metallic reinforcement over the column and for a flat slab floor in which the maximum value of the metallic reinforcement is attained by disposing the rods which constitute the reinforcement so that they will resist in greatest degree the positive and negative bending moments and the 20 diagonal tension or shearing stresses. This result is attained by providing crossed series or belts of rods which are disposed as near the top of the slab as possible and parallel thereto beyond the point of counter flexure, 25 so that maximum efficiency in resisting positive bending moment will result, and by providing a construction in which the belts of rods for resisting the positive bending moment will be disposed, as closely as possible and parallel to the bottom of the slab 30 or floor so that maximum efficiency in resisting positive bending moment will result, and in providing means between the top and bottom belts of rods which will effectively 35 resist diagonal tension or shearing stresses.

Another object of the invention is to provide 40 a metallic reinforcement over the column in the slab which comprises as an entity a series of connected rods to facilitate placement into position in the course of construction of the building. By providing these connected series of rods or mats, the likelihood of irregular or improper placement and the resultant defective reinforcement 45 will be overcome. Furthermore by forming these mats so they will include means for sustaining the lower belts of rods for resisting the positive bending moment, convenient supports are formed for lower 50 belts of rods which insure proper placement vertically and laterally in the structure.

A further object of the invention is to provide 55 a concrete structure in which the reinforcement is simple, inexpensive, may be readily placed in position and will ef-

ficiently serve to resist all the stresses to which the structure is usually subjected.

The invention consists in the several novel features hereinafter set forth and more particularly defined by claims at the conclusion 60 hereof.

In the drawings; Figure 1 is a section through a floor, the column being in elevation, embodying the invention. Fig. 2 is a detail plan of one of the metallic mats. 65 Fig. 3 is a plan showing the arrangement of the mats and slab reinforcement. Fig. 4 is a vertical section the columns being shown in elevation. Fig. 5 is a plan of a modified form of the invention in which angularly disposed stirrups are employed in the capitals. Fig. 6 is a vertical section on an enlarged scale of the form of the invention shown in Fig. 5. Fig. 7 is a detail of one of the stirrups. 75

The improved construction comprises a flat floor slab C of concrete, and columns B beneath the slab in desired number, according to the load to be carried by the floor. In the concrete slab above each column, or 80 between the superimposed columns, a metallic mat is disposed. Each of these mats is formed of rods and comprises two members A and A'. Each member of this mat is formed of a long strip bent into sinuous 85 form to provide a series of parallel rods connected by loops a at alternating ends. The rods of one member are disposed cross-wise of the rods of the other member of the mat, so that this metallic reinforcement over 90 the columns will have rods radiating or extending in four directions from the column, and there will be loops a at four sides of each mat. By employing mats of this character which comprise a large number of 95 rods connected by integral loops, it is not necessary for the workmen to exercise the great care necessary in separately laying a large number of metallic rods in order to bring each in its correct position to reinforce at the points desired, because the loops hold the rods of these mats in spaced relation. The mats can be more economically 100 handled than separate rods, since they are made at the factory and shipped to the place of building, already formed. In other words, in lieu of handling a large number of rods, it is only necessary for the workmen to place a lower member of the mat in its true and correct position over the col- 105

110

umn or where the column is to be placed and then lay the other member of the mat on it, or if desired, the two mat-members may be secured together before they are placed in 5 position and in that event, it is only necessary for the workmen to position the mat as an entirety.

The loops *a* respectively on the sides of the mat extend downwardly therefrom to 10 provide rests or supports in close proximity to the bottom of the slab and around the mat. Rods *D* are supported by said loops and extend from mat to mat, the rods being laid in the loops. Diagonal slab-rods *D'* extend 15 between the centers of the columns and continuously over the several spans. An important resultant feature of the employment of these mats with pendant loops or supporting-means at their sides, is that the 20 reinforced rods for the top and bottom of the slab are invariably disposed in properly-spaced relation according to the thickness of the floor, and furthermore these loops being spaced laterally from one another serve 25 to hold the bottom-rods in laterally spaced relation, during construction.

The rods constituting the mats are disposed close to the top of the slab and are parallel thereto to a point approximately 30 just beyond the point of counter-flexure. This disposition is important when metallic rods extending at right angles to one another are employed, because in this disposition maximum value of the metal is attained 35 and also maximum efficiency in resisting the negative bending moment. By disposing the belts of rods for resisting the positive bending moment in different directions between the columns and over them in substantial 40 parallel relation to the bottom of the slab and as near the bottom as practicable, maximum efficiency in resisting the positive bending moment will result so that by making it possible to derive maximum 45 value from these rods, their diameter will be such as to permit that undue thickness of the slab will be avoided. In this manner great economy is effected by the invention.

The structure set forth and exemplifying 50 the invention thus provides one in which the metallic reinforcement may be readily placed in position in the course of construction and in which the necessity of separately and accurately laying or supporting 55 a large number of rods will be avoided. Furthermore by employing reinforcement consisting of series of rods with pendant loops at the sides, a little care in the placement of these mats will insure proper placement 60 of the entire reinforcement, because the belts of rods for resisting the positive bending moment which are disposed at the bottom of the slab are supported and positioned by the mats.

65 The invention is not to be understood as

restricted to details set forth, since these may be modified by the skilled mechanic within the scope of the appended claims without departing from the spirit and the scope of the invention. Figs. 5, 6, and 7, 70 illustrate a modified form of the invention in which stirrups "J" extend diagonally through the capitals of the columns, and are looped around the rods of the mat. These stirrups reinforce the capital and are disposed so as to distribute the strains where a floor is unevenly loaded, the stirrup at load side serving as a compression, while the stirrup on opposite side of the column is subjected to tensile stresses. 80

The construction disclosed is one in which the slab reinforcement consists of belts or a series of parallel rods extending in four diametric directions from the column-head, and constitute what is generally known in 85 the art as a "four-way" reinforcement, and in which the belts or series of rods forming the reinforcement over the column-head and near the top thereof extend in two diametric directions only, and is of the character generally known as a "two-way" reinforcement. This avoids an excess of metal over the column-head and particularly in 90 the lower portion thereof, which is advantageous in a flat slab floor. 95

What I claim is:

1. A mat for a column head reinforcement in a flat slab floor construction, comprising members, each of which is formed of a series of rods arranged in substantially 100 parallel relation and in substantially a common plane and united at their alternate ends by end loops, the rods of one member crossing and overlying the rods of the other member, the looped ends of said rods being 105 extended downwardly to the lower portion of the slab.

2. A reinforced concrete structure, comprising columns, a flat slab floor, and mats for said columns, each of which comprises a lateral series of rods united at their alternate ends by end loops, the rods of one member of said mat crossing and overlying the rods of the other member, the looped ends of 110 said rods being bent downwardly, and bottom rods in the slab supported by said looped ends.

3. A reinforced concrete structure, comprising columns, a flat slab floor, and mats for column head reinforcement each of 120 which is formed of a lateral series of rods united at their alternate ends by end loops, the rods of one member crossing and overlying the rods of the other member, the looped ends of one member being disposed 125 between those of the other member, the loops of both members forming a circumferential series of supports around the mat, and bottom rods in the slab supported by said looped ends. 130

4. A mat member for a column head reinforcement in a flat slab floor construction, comprising a strip bent into sinuous form to provide a series of substantially parallel rods having connecting loops at alternate ends, said loops being bent downwardly to lie in the lower portion of the slab.
5. A reinforced concrete structure comprising columns, a flat slab floor, column-head reinforcement comprising rods disposed near the top of the slab and extending outwardly from the column beyond the point of counterflexure and having downwardly extending supporting means, and slab reinforcing rods extending between the column head reinforcement adjacent the bottom of the slab, held by said supporting means and terminating outwardly from the center of the column head and near the margin of the column-head reinforcement.
6. A reinforced concrete structure comprising columns, a flat slab floor, column head reinforcement comprising rods disposed near the top of the slab and extending outwardly from the column beyond the point of counterflexure and having downwardly extending supporting means, and slab reinforcing rods adjacent the bottom of the slab and held in said means, some of said rods extending to the center of the column-heads, and others terminating outwardly from the center of the column-head

and near the margin of the column-head reinforcement.

7. A reinforced concrete structure, comprising columns, a flat slab floor, and reinforcements comprising two-way rods over the columns in the tension zone near the top of the slabs and extending outwardly from the columns only slightly beyond the point of counter-flexure, four-way slab rods adjacent the bottom of the slab and extending between the columns, and supporting connections between the outer ends of said two-way rods and said four-way rods, the slab rods for two-ways being non-continuous over the columns.

8. A reinforced concrete structure, comprising columns, a flat slab floor, and reinforcements comprising two-way rods over the columns in the tension zone near the top of the slabs and extending outwardly from the columns only slightly beyond the point of counter-flexure, four-way slab rods adjacent the bottom of the slab and extending between the columns, and supporting connections between the outer ends of said two-way rods and said four-way rods, the two-way rods constituting the entire reinforcement in the tension zone above the columns.
